UNITED STATES PATENT OFFICE.

WILLIAM VOGEL, OF CHICAGO, ILLINOIS, ASSIGNOR OF THREE-FOURTHS TO
GARY G. CALKINS AND ADOLPH GRAY, OF SAME PLACE.

TELEPHONE.

SPECIFICATION forming part of Letters Patent No. 429,801, dated June 10, 1890.

Application filed August 19, 1889. Serial No. 321,221. (No model.)

To all whom it may concern:

Be it known that I, WILLIAM VOGEL, of Chicago, in the county of Cook and State of Illinois, have invented certain new and useful 5 Improvements in Telephones; and I do hereby declare that the following is a full, clear, and exact description thereof, reference being had to the accompanying drawings, and to the letters of reference marked thereon, which 10 form a part of this specification.

This invention relates to a novel telephone or device for transmitting vocal or other sounds between distant points by means of a metallic conductor extending between them.

15 An apparatus embodying my invention differs from devices for the same purpose heretofore employed in the use of magnetism instead of electricity as a medium by which sounds made in the vicinity of the transmitting-instrument are reproduced by the receiving-instrument of the apparatus.

I have found that a long metallic strand or wire connecting two distant stations between which it is desired to transmit vocal sounds 25 may be maintained in magnetic condition either by permanently magnetizing such strand, if of steel, or by surrounding the same by an electric conductor or conductors forming part of an electric circuit or circuits. 30 In either case opposite magnetic poles are produced at opposite ends of such strand or wire and a plurality of neutral points and magnetic poles established at intermediate points along the same. I have found, furthermore, that when an armature located 35 opposite one end of such magnetized strand or wire is caused to vibrate corresponding vibrations will be set up in an armature supported opposite the other end of such magnetized strand, it being a well-known fact that in the case of ordinary magnets any 40 changes in the magnetic condition of one pole produced by the movement of an armature or otherwise will result in corresponding changes in the magnetic condition of the other or opposite pole of the magnet.

An apparatus embodying my invention consists in its main or essential features of a magnetized metallic strand or wire, which reaches 45 50 from the transmitting to the receiving station,

combined with armatures located at opposite poles or ends of said strand or wire. In the operation of the apparatus when the armature at one pole is set in vibration by a sound in its vicinity the armature at the opposite end of the strand or wire is caused to vibrate in unison with the armature at the point of transmission, and thereby reproduces accurately sounds occurring at such point of transmission. In practice the vibrating armatures 55 referred to preferably consist of diaphragms, which are supported opposite and adjacent to the poles of the magnet in the same manner as heretofore common in electric telephones.

The invention above set forth in general 60 terms may be carried out in practice for the use of a great number of different forms of apparatus.

In the accompanying drawings, Figure 1 is a diagram illustrating a simple form of my 70 invention, showing a single electric circuit employed to magnetize the strand or wire forming the core of the electro-magnet. Fig. 2 is a similar diagram showing a strand or wire in which magnetism is induced by a plurality of electric circuits. Fig. 3 is a diagram showing a strand or wire and a series of separate spools of electric conductors thereon. Fig. 4 is a diagram showing an apparatus which differs from that shown in Fig. 1 by 75 having the strand or wire forming the magnet-core arranged to form part of the electric circuit. Fig. 5 illustrates a permanent magnet employed to transmit vibratory motion from one armature to another. Fig. 6 shows a 80 metallic strand which is magnetized by a plurality of permanent magnets. Fig. 7 illustrates one practical way of arranging the coils of the electric circuit about the magnet-core. Fig. 8 illustrates partially in side view the main parts 85 of one practical form of apparatus embodying my invention. Fig. 9 is enlarged at the section of one of the magnet-pole pieces and exciting-coils therefor shown in Fig. 8. Fig. 10 is a sectional view of a casing or shell which 90 supports the vibrating armature or diaphragm. Fig. 11 is a face view of the casing or shell shown in Fig. 10. Fig. 12 is a sectional view taken upon line 12 12 of Fig. 9. Fig. 13 is a 95 sectional view taken upon line 13 13 of Fig. 9. 100

As shown in the said drawings, Fig. 1, A A' indicate pole-pieces of soft wire, and B a soft-iron wire or strand extending between and connecting the same and forming with the 5 pole-pieces the core of an electro-magnet.

C C' are diaphragms arranged respectively opposite the pole-pieces A and A', and D is an electric wire or conductor, which is coiled around the pole-pieces A and A', and the wire 10 B connecting them, and is connected with the opposite poles of a battery D', said conductor D being insulated in its part which surrounds said pole-pieces and the connecting-wire. The conductor D is coiled or wound in the same 15 direction on both of the pole-pieces A and A' and on the intermediate wire B, so that the current maintained in the circuit formed by said wire and the battery D' will operate to establish a magnetic condition in the said 20 pole-pieces and the wire, making one of said pole-pieces of north and the other of south polarity. Each pole-piece and diaphragm forms an apparatus adapted either for transmitting or receiving. The connecting strand 25 or wire B may be of any length desired, provided that the electric current sent through the conductor D is of sufficient strength to maintain in magnetic condition the pole-pieces AA', and the strand D, which together 30 with the said conductor constitute an electro-magnet, having a series of intermediate poles between its ends, as is common in long magnets.

I have found by experiment with an apparatus constructed as described that when a 35 noise or sound of vocal or other character is produced in the neighborhood of the one of the diaphragms C a corresponding sound will be produced by the diaphragm C', or vice 40 versa, the reason for this being, as far as I have been able to ascertain, that any charges in the magnetic condition of one of the pole-pieces, due to the vibration of the diaphragm adjacent thereto, are reproduced 45 in the other pole-piece and give corresponding movement to the armature adjacent to such pole-piece, it being well understood that any variations in the magnetic condition or intensity of one pole-piece of any magnet, 50 whether a permanent or electro-magnet, will be followed by corresponding changes in the magnetic condition of the other pole of the magnet.

I have found that it is not essential for the 55 working of the telephonic apparatus of the character described that the magnetic condition in the connecting wire or strand be maintained by the use of a single electric circuit only, but a plurality of electric circuits may 60 be employed for this purpose, provided they are arranged to give a circuit around the wire or strand in the same direction and are thereby adapted to establish opposite magnetic poles in the same. In Fig. 2, for instance, I have shown the main parts or elements of an apparatus similar to that shown 65 in Fig. 1, and having pole-pieces A and A'

connected by a wire B and diaphragms C and C'. In this instance a plurality of electric circuits E E' E² E³ E⁴ are employed, each of 70 which include separate electric batteries e e' e² e³ e⁴.

In Figs. 1 and 2 the electric conductor is shown as wrapped about the connecting strand or wire throughout the entire length of the 75 same, but this construction, although desirable in some instances, is not essential, inasmuch as separate compact coils arranged at intervals upon the said strand or wire may be employed with the same practical result. 80 A construction of this kind is shown in Fig. 3, wherein A A' indicate pole-pieces and B a wire strand or core connecting the same. F F' are coils or electric conductors surrounding said pole-pieces and arranged in circuit 85 with batteries f f'.

F² F² F² are intermediate coils of electric conductors placed around the strand or wire B at points intermediate to the pole-pieces. Said conductors F² are arranged in circuit 90 with batteries f² f². In a construction of this kind the coils F² F² serve to form in fact a series of electro-magnets having their poles in contact with each other, so as to maintain magnetic condition in the entire length of the 95 connecting-wire even when the same is of great length.

In Fig. 4 I have illustrated an apparatus embodying my invention in which the electric circuit by which a magnetic condition is 100 maintained in the soft wire strand or wire is completed through the strand or wire itself. In this instance A A' are pole-pieces, and B a wire connecting the same. C C' are dia- 105 phragms arranged adjacent to the pole-pieces, and D³ is an electric conductor connected with opposite electrodes of a battery D³. The conductor D² is arranged in two coils D⁴ D⁵ about the pole-pieces A and A', and is wrapped spirally about the wire B throughout 110 its entire length. The battery D³ is shown in said Fig. 4 as located adjacent to one of the pole-pieces A, and the conductor D², which extends along the wire B and is connected with one electrode of the battery, has elec- 115 trical connection with the pole-piece A', while that part of said conductor D² connected with the opposite electrode of the battery has electrical connection with the said wire B at a point adjacent to the battery. The part 120 of the conductors surrounding the wire B and the pole-pieces is of course covered with insulated material, as before described, so that by connecting the conductor with the said wire B and pole-piece A' in the manner de- 125 scribed an electric circuit is completed through the said pole-piece and wire. This construction is of advantage, for the reason that it renders unnecessary the employment of a third wire to complete the electric cir- 130 cuit. This is obviously a matter of great importance, inasmuch as it enables the telephone to be constructed by the use of two wires or strands only—to wit: the wire or

strand forming the extended core of the magnet and an insulated wire wrapped about the same and forming part of the electric circuit. It will be noted in this connection that I have 5 found by experiment that the passage of the electric current through the wire forming the magnet-core has no effect whatever upon the magnetic action of the same.

- In Fig. 5 I have shown a simple or elementary form of apparatus embodying my invention, which may be used where the distance between the transmitting and receiving instruments is not great. In this instance I employ a steel rod or wire which extends 10 from the transmitting to the receiving instrument, and which is permanently magnetized so as to form a magnet having opposite poles at its opposite ends and a series of intermediate poles. At the opposite ends or 15 poles of said magnet are located diaphragms which form with the polarized ends of the magnet the transmitting and receiving elements. As shown in said Fig. 5, G indicates a magnetized steel rod or wire which reaches 20 from the transmitting to the receiving instrument, and H H' indicate diaphragms which are located opposite and adjacent to the poles of the magnet. When one of said diaphragms is set in vibration by means of 25 sound-waves impinging thereon, the magnetic condition of the adjacent pole of the magnet G is caused to change or vary, thereby producing corresponding changes in the opposite pole of the magnet, whereby vibrations 30 are produced in the second or receiving diaphragm with the result of reproducing the sounds made in the vicinity of the transmitting diaphragm, in the same manner as heretofore described.
- In Fig. 6 I have shown the elements of a telephonic apparatus of the kind above referred to, embracing an iron or steel wire, which is maintained in magnetic condition by permanent magnets disposed at intervals along the wire. 35 In this instance I I' are permanently magnetized pole-pieces, adjacent to which are located armatures or diaphragms J J'. I² I² are intermediate permanently-magnetized steel bars or magnets, which are connected with 40 each other and with the magnets I and I' by means of wires K K K. The intermediate magnets I² I² are disposed at such distances apart as to maintain the connecting wire or rod permanently in a magnetic state, and by 45 multiplying said permanent magnets and connecting-pieces the length of the magnetized strand between the transmitting and receiving instruments or stations may be increased indefinitely.
- Fig. 7 is a diagram illustrating a simple 50 form of apparatus embodying my invention, wherein a single electric circuit is employed to magnetize the entire length of the connecting-wire of the apparatus. In this instance L L' are pole-pieces, which are connected with 55 each other by a soft-iron wire M.

N is a circuit-wire, which is wrapped about the pole-pieces and wire M, and is connected with a battery or other electric generator indicated by n. The ends of the conductor N 7c are connected with the pole-pieces L L', as indicated at n' n', so that said pole-pieces and the wire M form part of the electric circuit. The conductor N is preferably wound to form two large or thick coils N' N', surrounding 7s the pole-pieces L L', so as to produce a strong magnetic condition in the said pole-pieces.

O O' are diaphragms located adjacent to the pole-pieces L L' in the same manner as hereinbefore described. 80

In Figs. 8 and 13 I have illustrated one way in which I have carried out my invention in practice. In this instance P P' are two pole-pieces, which are connected by a core-wire Q.

R is an electric conductor connected with 85 the opposite poles of the battery or generator r, and wrapped about the core-wire Q and pole-pieces P P'. The extreme end of the pole-pieces of the conductor R is wound in a manner to form a thick coil or bundle of 90 wires R', and the ends of the conductor are connected with the pole-pieces, as indicated at r'.

S S' are electric conductors which surround 95 the pole-pieces P P', and which are in circuit with local batteries s s'. The current flowing through said conductors S S' serves to reinforce or strengthen the poles of the magnet. The several conductors R and S S' are covered with insulating material in their parts 100 adjacent to the pole-pieces and core-wire.

T T' is a metal shell or casing adapted to be placed over the ends of the pole-pieces of the magnet and provided with a diaphragm U, which is located adjacent to the pole-piece 105 when the shell is in place. The shell T is provided with an outer wall T', which covers the diaphragm and is provided with a central aperture forming a mouth-piece for the transmitting devices. To enable the instrument 110 to be conveniently used both for receiving as well as transmitting, the casing T is conveniently provided with a flexible tube t', to the end of which is attached a tubular ear-piece T², which may be placed against the ear and 115 will serve to convey thereto sounds produced by the diaphragm. The casing T is herein shown as sustained by means of a stationary plate V, which is sustained by attachment to a wall, as shown, or otherwise surrounds the 120 pole-piece P. Said plate V is shown as provided with a flange p, over which the open end of the shell may be slipped and held by frictional engagement, thereby enabling the shell and diaphragm therein to be removed 125 and replaced when desired. V' indicates a shell or covering, which may be conveniently placed over or around the end of the pole-piece and the wire coil R' thereon to protect the latter from injury when the shell T is removed. 130

The conductor-wires forming the electric

circuit in either of the cases described may be wound more or less closely about the connecting or core wire. In Figs. 7 and 8, for instance, such conductor-wire is shown as wrapped closely about the core-wire with its adjacent coils or turns in contact with each other; but in Figs. 1, 2, and 4 it is shown as wound thereon in separate or open turns, and this will commonly be a preferred construction in cases where the electric circuit-conductor extends throughout the entire length of the core-wire.

I have herein shown a battery as employed as a means of generating the length of current; but other electric generators—such as a dynamo or magneto electric machine—may be employed for the same purpose. It will be obvious, for instance, that in telephonic apparatus employed for long distances the current from a dynamo-electric machine may be employed to maintain in magnetic condition a connecting strand or core wire of great length.

I claim as my invention—

1. A telephone embracing a magnetized strand or core extending between the transmitting and receiving points or stations, and transmitting and receiving devices comprising vibrating armatures located adjacent to

the ends or poles of said magnetized strand 30 or core, substantially as described.

2. A telephone embracing a metallic strand or core extending between the transmitting and receiving points or stations, an electric circuit comprising a coil or coils surrounding 35 said metallic strand or core, and transmitting and receiving devices comprising vibrating armatures located adjacent to the ends or poles of said strand or core, substantially as described.

3. The combination, with a magnetized strand or core extending between transmitting and receiving points or stations, and a combined transmitting and receiving device comprising a diaphragm arranged adjacent to 45 the end or pole of said strand or core, and a shell or casing surrounding the diaphragm and provided with a mouth-piece, and also with a flexible tube having an ear-piece in communication with the interior of the said 50 shell or casing, substantially as described.

In testimony that I claim the foregoing as my invention I affix my signature in presence of two witnesses.

WILLIAM VOGEL.

Witnesses:
